(57) **CLAIM**

The ornamental design for a chase wall clip as shown and described.

DESCRIPTION

FIG. 1 is a top, front isometric view of a first embodiment of a chase wall clip, showing our new design;

FIG. 2 is a top, plan view of the chase wall clip of FIG. 1; FIG. 3 is a bottom, plan view of the chase wall clip of FIG. 1;

FIG. 4 is a front elevational view of the chase wall clip of FIG. 1, which the rear elevational view is a mirror image thereof;

FIG. 5 is a right side elevational view of the chase wall clip of FIG. 1, which the left side elevational view is a mirror image thereof;

FIG. 6 is a top, rear isometric view of the chase wall clip of FIG. 1 incorporated into a wall assembly;

FIG. 7 is a top, front isometric view of a second embodiment of a chase wall clip, showing our new design;

FIG. 8 is a top, plan view of the chase wall clip of FIG. 6; FIG. 9 is a bottom, plan view of the chase wall clip of FIG. 6;

FIG. 10 is a front elevational view of the chase wall clip of FIG. 6, which the rear elevational view is a mirror image thereof;

FIG. 11 is a right side elevational view of the chase wall clip of FIG. 6, which the left side elevational view is a mirror image thereof; and,

FIG. 12 is a top, rear isometric view of the chase wall clip of FIG. 6 incorporated into a wall assembly.

The broken lines in FIGS. 1-12 are included for purposes of illustrating portions of the chase wall clip or environmental structure that form no part of the claimed design. The chase wall clip is shown with symbolic breaks in its length. The symbolic breaks are depicted using separation and brackets.

(Continued)

The appearance of any portion of the chase wall clip between and including the separations and brackets forms no part of the claimed design.
